UNITED STATES PATENT OFFICE.

FRANK E. HANNULA AND WILLIAM E. TROMBLEY, OF LANSING, MICHIGAN.

CAN RUBBER.

Application filed May 20, 1922. Serial No. 562,552.

To all whom it may concern:

Be it known that we, FRANK E. HANNULA and WILLIAM E. TROMBLEY, citizens of the United States, residing at Lansing, in the 5 county of Ingham and State of Michigan, have invented a new and useful Improvement in Can Rubbers, of which the following is a specification.

Our invention relates to can rubbers for 10 sealing ordinary self-sealing cans for preserving fruits, of the Mason or similar types. It has for many years been common to seal these cans by means of a rubber ring, and in consequence of the sticking of the ring and 15 cover, it has been very difficult to remove the lid. The purpose of our invention is to obviate this difficulty by so constructing the rubber ring that it shall be readily torn across and removed thus leaving the lid loose. 20 We attain this purpose by the means shown in the accompanying drawings in which Figure 1 is a plan view of our improved ring, the position of the reinforcing strip being indicated by dotted lines. Figure 2 is a 25 view of the edge of the ring, the reinforcing strip being there also indicated by dotted lines. In the drawings, 1 is the main body of the ring, which is of the usual form, but is provided at some point of its circumference with a projecting tongue, 2, that will 30 project beyond the cover when the ring is in position and the cover applied, and thus furnishing a convenient hold for the fingers for tearing or removing the ring. A notch,

3, is made in the outer margin of the ring 35 close to one side of the tongue, 2, to furnish a starting point for the tearing across of the ring. A reinforcing strip, 4, of fibrous material is preferably imbedded in the tongue to prevent the tongue, 2, from tearing off 40 without breaking the ring.

The operation of our device is as follows:

The person desiring to remove the top 45 from the can takes hold of the tongue, 2, and pulls it. The rubber ring then tears 45 across starting from the notch, 3. This breaks the ring and it is readily pulled out from under the cover.

We claim as our invention and desire to 50 secure by Letters Patent:

1. An article of the character described, 55 comprising a ring formed of any suitable material and provided on its outer margin with an integrally formed projection adapted to be grasped by the fingers, and a notch adapted to facilitate the rupture of said ring.

2. An article of the character described, 60 comprising a ring formed of any suitable material and provided on its outer margin with an integrally formed projection adapted to be grasped by the fingers, a notch adapted to facilitate the rupture of said ring, and a strengthening piece of suitable material imbedded in said projection and ring.

FRANK E. HANNULA.

WILLIAM E. TROMBLEY.
